UNITED STATES PATENT OFFICE.

JOSEPH W. HOODWIN, OF CHICAGO, ILLINOIS.

CRIMPING AND FOLDING MACHINE.

1,353,590.

Specification of Letters Patent. Patented Sept. 21, 1920.

Application filed March 3, 1920. Serial No. 362,944.

To all whom it may concern:

Be it known that I, JOSEPH W. HOODWIN, a citizen of the United States, and a resident of Chicago, in the county of Cook and State of Illinois, have invented certain new and useful Improvements in Crimping and Folding Machines, of which the following is a specification.

My invention relates to an improved crimping and folding machine which is particularly useful for crimping strips of paper previously transversely perforated, and then transversely folding the strip so that the small folded together compact sections of the strip may be readily detached therefrom and from one another.

In a machine of this class, crimping rolls are usually provided for longitudinally crimping the previously transversely perforated strips, and then the crimping strips are subjected to transverse pressure preferably under the application of heat, to compactly press together the overlapping folds so that the strip can then be readily separated into compactly folded sections or pellets which can readily be inserted in small openings or pockets. My invention involves improved structure and operation for feeding paper blanks to the crimping rolls and from there to the pressure mechanism, an important object of my invention being to provide improved and more efficient means for compressing the crimped strips and for preventing distortion thereof during the pressing operation. Another important object is to provide improved means for discharging the crimped and folded strips from the machine. These, and other features of the invention are incorporated in a structure disclosed on the accompanying drawings, in which drawings—

Figure 1 is a plan view of the machine,

Fig. 2 is a front elevational view,

Fig. 3 is a side elevational view,

Fig. 2.

The supporting framework for the machine parts comprises the top or table part 1, and the sides 2 and 3. Journaled in the sides is the main drive shaft 4 shown as driven by belt 5 engaging the pulley 6 at one end. At the other end of the shaft is the sprocket wheel 7 connected by the chain 8 with the sprocket wheel 9 at the corresponding end of the shaft 10 which supports the lower crimping roll 11, this shaft being journaled in the vertical extensions 12 and 13 on the sides 2 and 3. Above the shaft 10 the shaft ends of the upper crimping roll 14 are journaled in bearing boxes 15 and 16 which are vertically slidable in openings 17 and 18 in the extensions 12 and 13. Extending between and secured to the upper ends of the extensions 12 and 13 is the top plate 19 which supports the set screws 20 and 21 in register with the openings 17 and 18, these set screws bearing against springs 22 and 23 which engage with the journal boxes 15 and 16 respectively so that the upper crimping roll is pressed yieldingly against the lower crimping roll.

In front of the crimping rolls and supported on the table 1 is the shelf 24 along which are fed the paper strips *s* which are to be crimped. This table has transversely extending slots 25 through which project the feed fingers 26 which extend upwardly from the rectangular frame 27 secured at its lower ends on the shaft 28 which is journaled in the sides 2 and 3 parallel with the drive shaft 4. The movement of this feed frame is controlled by cam mechanism which will be described in detail later. A paper strip *s* is laid on the shelf 24 in front of the projecting fingers and when the feed frame is swung toward the crimping rolls, the strip is fed into the rolls and received by the crimping projections *c* to be carried thereby through the rollers to the other side thereof. In order to prevent the crimped strips from traveling around with either one of the crimping rolls after the crimping operation, guard wires 29 and 30 are provided for the

upper and lower crimping rolls respectively. The wires 29 are suspended from a bar 31 which extends between the sides 2 and 3 behind the upper crimping roll, the free ends 5 of the wires extending through circumferential grooves 32 in the upper crimping roll as clearly indicated in Fig. 4. Secured to the sides 2 and 3 and extending along the rear side of the lower crimping roll is the 10 supporting bar 33 which carries a plurality of supporting brackets 34 for the various guard wires 30, the guard wires at their front ends being supported by the table 24. As shown, the ends extend through holes 35 15 in the table to be then riveted or otherwise secured against the under side of the shelf. The wires extend through the circumferential grooves 36 formed in the lower crimping roll, and with these upper and lower guard 20 wires the crimped strip has no chance to follow one of the crimping rolls but is extracted therefrom by the guard wires and falls down along the lower guard wires to be deposited on the table 1 behind the crimping rolls. 25

The shape of the crimped strip when it reaches the table is clearly shown in Fig. 4, and it is now ready to be pressed transversely to have its folds compactly brought 30 together.

The pressing mechanism and its operation are clearly shown in Figs. 4 to 8. The side walls 2 and 3 are cut out just above the table 1 to leave the slots 37 and 38 for receiving the bearing ends 39 and 40 of the presser bar 41. Between the bar and its bearing ends are the reduced cylindrical sections 42 and 43 for receiving the slotted upper ends of the arms 44 and 45 extending 35 upwardly from and secured to the shaft 46 which is journaled in the side walls 2 and 3. By suitable cam mechanism to be described in detail later, these arms are swung to carry the presser bar along the top of the 40 table with its bearing ends 39 and 40 engaging in the slots 37 and 38. A short distance behind the inner ends of the slots 37 and 38 the table has the abutment step 47 between which and the presser bar the crimped 45 strips are deposited on the table from the crimping rolls. When the presser bar travels inwardly, it encounters a deposited crimped strip and carries it toward the abutment step 47 and then, as shown in Fig. 5, the strip is compressed between the bar 50 and the abutment to have its folds compactly brought together into parallelism. Unless provision is made for preventing, the crimped strips when shifted along the 55 table by the presser bar will tend to buckle and would not be compressed together accurately along the folding lines established by the crimping process. I therefore provide a guard or vertical presser plate 48 60 which is normally in position to permit dis-

charge of a crimped strip from the crimping rolls to the table and which is then brought into parallelism with but a distance away from the table to provide a guide passageway for the crimped strip 70 during its travel toward the abutment step 47. The construction and operation of this plate 48 is best shown in Figs. 4 to 7. The plate along its rear edge is semi-circular and rests on top of the step 47. Extending 75 from its ends a short distance in front of the center of curvature of the semi-circular edge are the pins 49 and 50 which are engaged by the hooked front ends of the levers 51 and 52 which at their rear ends 80 bear against the table. Each bar has the opening 53 therethrough through which extends a headed bolt 54, the bolts projecting through the openings 55 through the table and supporting the compression springs 56 85 which abut at their upper ends against the under side of the table and at their lower ends abut against washers 57 held to the bolts by the nuts 58. The springs are always under compression so that the bolts 90 exert downward pull on the levers 51 and 52, which pull or pressure is conveyed to the pins 49 and 50, such pressure tending to swing the guard plate 48 downwardly. Extending from the plate downwardly through 95 the opening 59 of the table is the arm 60 which at its lower end is pivoted to the bar 61 which is shifted longitudinally by cam mechanism to be described later. Normally, the bar is held to cause the plate 48 to be 100 held upwardly in inclined position as shown in Fig. 4 to permit discharge of crimped strips to the table. The bar 61 and its cam mechanism coöperate with the spring levers 51 and 52 to swing the guard plate downwardly into parallelism with the table as shown in Fig. 5, after the crimped strip has been delivered to the table. When the presser bar 41 presses the crimped strip against the abutment 47 the primarily inclined folds of the strip become vertical so that the height of the strip increases. It is, however, desirable that the strip during the transverse pressing or compact folding operation be at all times in engagement with 110 the table and with the plate 48 so as to prevent buckling and improper folding. This is permitted by the springs 56 which tend to hold the plate 48 down in position of engagement with the tops of the strip folds 115 and to yield as the height of the strip is increased during the compact folding operation. The crimped strip during the folding up and compressing operation is therefore always engaged on all four sides and it 120 must necessarily fold accurately along the lines established by the crimping rolls. 125

I preferably apply heat to the crimping rolls and also to the table section along which the crimped strip travels during the 130

folding and pressing operation, such heating insuring retention of the shape and form into which the strip is crimped and pressed. As shown heating nozzles 62 extend downwardly from a gas supply pipe 63 to direct flame against the upper crimping roll. A gas pipe 64 supplies gas below the table for heating that section on which the crimped strips travel.

10 I preferably provide longitudinally extending grooves 65 in the table top and register grooves 66 in the under side of the plate 48. I find that such grooves prevent buckling of the table and the plate under heat. The grooves also serve to receive the guide tongues 67 and 68 on the lower and upper sides of the presser bar 41. These tongues accurately guide the bar when traveling between the table and the plate 48 and 15 also serve to strengthen the bar and prevent its buckling.

After folding up of the crimped strip under pressure and heat it is ready to be discharged from the machine. The discharging mechanism is best shown in Figs. 1, 3, 5 and 6. Ejector bars 69 are applied in the 20 grooves 65 and at their rear ends these ejector bars receive the rod 70 which extends through the slotted end of the Y frame 71 which at its lower end is secured to the shaft 25 72 extending between the side walls 1 and 2. Cam mechanism to be described later swings this Y lever to cause reciprocation of the ejector bars. Normally the front ends of 30 the ejector bars are behind the abutment 47. After the presser bar 41 has been returned after a pressing operation, the ejector bars are shifted forwardly through the grooves 35 65 and carry the finished strips forwardly 40 and deposit them on the delivery apron 73.

The cam mechanisms heretofore referred to are clearly shown in Figs. 2 and 3, and 9 to 12. In Fig. 9 is shown the cam control for the feed frame 27. Extending from this 45 frame is the link 74 whose longitudinal slot 75 receives the main drive shaft 4 on which is secured the cam disk 76. This disk has the cam groove 77 which extends concentrically for about 270 degrees and which for 50 the remaining distance has the V-shaped path 77' deflecting toward the center of the disk. In the cam groove rolls the cam roller 78 pivoted on the link 74, and as the cam disk rotates, the cam groove will coöperate 55 with the cam roller to periodically swing the feed frame 27.

The cam mechanism for assisting the spring levers 51 and 52 in controlling the operation of the guard plate 48 is shown in 60 Fig. 10. The bar 61 connected with the plate has the longitudinally extending slot 79 near its lower end which receives the driving shaft 4 on which is secured the cam disk 80 which has the concentric cam surface 65 81 extending through about 120 degrees.

Journalized on the inner end of the bar 61 is the cam roller 82 which engages with the cam surface. The force of the springs 56 acting through the levers 51 and 52 and the plate 48 hold the cam roller against the cam 70 surfaces of the cam 80. Whenever the roller engages with the concentric surface 81 the plate 48 will be held in raised position. When the roller travels along the cam surface 83 toward the hub of the cam the 75 spring levers 51 and 52 will be free to swing the plate 48 downwardly to the table.

In Fig. 11 is shown the cam mechanism for controlling the operation of the presser bar 41. On the arm 44 which supports one 80 end of the presser bar is the cam roller 84 which engages in the cam groove 85 in the disk 86 secured to the main drive shaft 4. This cam groove has the outer section 85^a concentric and of substantially 90 degrees 85 extent, and has the inner section 85^b of substantially 90 degrees extent and also concentric but of less radius than that of the section 85^a. The ends of the sections 85^a and 85^b are joined by the sections 85^c and 90 85^d.

In Fig. 12 is shown the cam mechanism for controlling the operation of the ejector bars. The frame 71 at intermediate parts receives the link 87 whose inner end has the 95 longitudinal slot 88 receiving the main drive shaft 4. At its end the link has the cam roller 89 which travels in the elliptical cam groove 90 whose inner section 90^a is concentric and extends about 180 degrees. The 100 cam groove is formed in the disk 91 secured on the shaft 4.

Describing now the sequence of operation, let us begin with the position shown in Fig. 4. A crimped strip has just been 105 delivered to the table and the cam roller 78 is in the long concentric groove 77 of cam 76 so that there will be no feeding of paper to the crimping rollers for some time. The cam roller 82, however, is just about to leave 110 the concentric cam surface 81 to rapidly travel over the surface 83 and then to the concentric cam surface of the cam hub (Fig. 10). The resulting movement of the bar 61 will permit the spring levers 51 and 52 to 115 swing down the plate 48 to form the upper wall of the guideway for the crimped strip. While the cam roller 82 is in engagement with the concentric cam hub the guard plate 48 stays in its horizontal position, and during this time the groove section 85^c of the cam 86 is effective to swing the arms 44 and 45 to shift the presser bar 41 rearwardly to fold up the crimped strip and press it against the abutment 47. While the cam 125 groove 85^a, which is concentric, is acting on the cam roller 84, the presser bar 41 remains in its rear position to hold the paper compressed while it is being heated. During compression of the strip the plate 48 can 130

yield to compensate for the increased height of the strip as was before explained.

After the compression operation, the cam 80 becomes effective to draw down the bar 62 to raise the plate 48 and the groove section 85^a of the cam 86 becomes effective to swing the levers 44 and 45 to cause the presser bar 41 to be shifted outwardly.

While the cam roller 84 is in the concentric 10 groove section 85^a and the cam roller 82 is engaged by the concentric surface 81 of the cam 80, ejector mechanism comes into operation to eject the finished strip. The cam roller 89 in the cam 91 leaves the concentric 15 groove section 90^a and is shifted to swing the frame 71 forwardly so that the ejector bars are shifted forwardly through the grooves 65 and the finished strip is discharged from the table onto the apron 73.

20 After ejection of a finished strip the cam 76 becomes effective to cause rearward swing of the feed frame and the blank paper strip placed on the shelf 24 will be fed to the crimping rolls by the fingers 26 and after 25 crimping of the strip it is delivered to the table in position shown in Fig. 4, whereafter the same operations are carried through as above described. If desired, a cam 86' similar to cam 86 may be associated with the 30 arm 45 connected with the presser bar 41.

These two cams equalize the pressure exerted by the bar and the bar will travel smoothly and will not bind. Engagement 35 of the tongues 67 and 68 on the presser bar in the groove of the table and the plate 48 serves another useful purpose. It prevents the thin paper of the strip from entering or being caught between the presser bar and the table or the plate.

40 I thus produce a very efficient machine for longitudinally crimping and transversely folding under pressure strips of paper previously transversely perforated so that the finished product can be readily divided into 45 pellets by breaking at the perforation line.

There is no danger anywhere in the machine of the strip becoming caught or torn, and on account of the yielding guard plate 48 which in coöperation with the table always keeps 50 the crimped strip from displacing vertically, there is no chance for buckling and the crimped strips must be permanently folded along the lines determined by the crimping process. Changes and modifications 55 are no doubt possible which would still come within the scope of the invention and I do not therefore desire to be limited to precisely what I have shown and described.

60 I claim as follows:

1. In a crimping and folding machine, the combination of a supporting table, crimping rolls above said table, means for feeding paper strips to the crimping rolls, 65 said rolls delivering the crimped strips to

said table, an abutment on said table, a presser bar slidable on said table to press the crimped strips against said abutment to intimately fold them, and means for exerting vertical pressure on the strips during 70 folding thereof.

2. In a crimping and folding machine, the combination of a supporting table, crimping rolls journaled above said table, means for feeding paper strips to said 75 crimping rolls, the crimped strips being delivered from said rolls to said table, an abutment on said table, a presser bar and means for reciprocating it on said table, said bar engaging with the crimped strip to press it 80 against said abutment to permanently bring together the folds thereof, a guard plate removably held above said crimped strip and the path of said presser bar, said guard plate and table confining the crimped strip 85 vertically to prevent buckling thereof during compression thereof by the presser bar, and means for ejecting the finished strip from said table.

3. In a crimping and folding machine, 90 the combination of a supporting table, crimping rolls journaled above said table for crimping paper strips and delivering them to said table, an abutment on said table, a presser bar and means for forcing 95 said bar toward said abutment to transversely compress a crimped strip against said abutment, a guard plate, means for normally holding said guard plate raised from said table to permit feed thereto of a 100 crimped strip, means for lowering said plate into parallelism with said table over a crimped strip after feed to the table of the strip, said plate and table forming a confining passageway for the strip through 105 which the bar travels to effect compression thereof, and means for discharging a compressed strip from said table.

4. In a crimping and folding machine, the combination of a supporting table, upper and lower crimping rolls journaled above said table, means for feeding paper strips to said crimping rolls to be longitudinally crimped, means for guiding crimped strips from said rolls to said table, 110 an abutment on said table, a presser bar slidable on said table toward and away from said abutment, means for controlling the reciprocation of said bar, a removable guard plate above the table forming a passageway therewith through which a crimped strip is shifted by the presser bar to be eventually compressed between said bar and said abutment, and means for discharging a compressed crimped strip from said table. 115

5. In a paper crimping and folding machine, the combination of a supporting table, crimping rolls journaled above said table for crimping paper strips and discharging them to said table, a presser bar recipro- 120 125

cable on said table, an abutment on said table, a removable guard plate a distance above and parallel with said table to leave a passageway for a crimped paper strip 5 and said bar, said bar eventually compressing said strip against said abutment, grooves in said table and plate, and tongues in said bar for engaging in said grooves.

6. In a crimping and folding machine, 10 the combination of a supporting table, crimping rolls journaled above said table, means for feeding a paper strip to said crimping rolls to be crimped thereby, means for guiding crimped strips from said rolls 15 to said table, a guard plate normally raised to permit discharge of a crimped strip to the table from the rolls, means for lowering said plate into parallelism with but a short distance above said table to form an 20 upper retaining wall for the crimped strip, an abutment between the table and the end of said plate, a presser bar mounted on said table, means for shifting said bar between said table and plate to engage with and 25 compress the crimped strip against said abutment, and means for discharging the compressed strip from said table.

7. In a crimping and folding machine, the combination of a supporting table, 30 means for discharging a crimped strip to said table, a guard plate over said table forming a passageway therewith for the crimped strip, an abutment at the end of said passageway, a presser bar mounted on 35 said table, means for shifting said bar into said passageway to fold up said crimped strip and press it against said abutment, said guard plate being vertically yieldable during the compression operation, and 40 means for discharging the compressed strip from the plate.

8. In a crimping and folding machine, the combination of a supporting table, crimping rolls for crimping paper strips, means for 45 guiding crimped strips from said rolls to said table, an abutment ridge on said table, a guard plate hinged on said abutment plate and normally raised to permit said table to receive a crimped strip, means for swinging the plate into parallelism with said table to 50 form a passageway therewith, a presser bar guided on said table, means for shifting said presser bar into said passageway to engage with and to compress the crimped strips 55 against said abutment, said plate being vertically yieldable to permit increase in height of said crimped strips during compact folding thereof against said abutment, and ejector arms for ejecting a compressed strip 60 from said table.

9. In a crimping and folding machine, the combination of a supporting table, vertical extensions at the sides of said table, crimping rolls journaled in said extension above 65 said table, means for feeding a paper strip

to said rolls, means for guiding a crimped strip from said rolls to said table, said vertical extensions having guide slots just above said table, a presser bar guided in said slots and reciprocable across said table, an abutment at the end of said slots in front of which a crimped strip is deposited from the crimping rolls, said presser bar upon its inward travel engaging with the crimped strip and compactly folding it together and 70 compressing it transversely against said abutment, and means for exerting vertical pressure on the strips during such transverse compression and folding thereof.

10. In a crimping and folding machine, 80 the combination of a supporting table, extension walls at the sides of said table, crimping rolls journaled in said extension walls above said table, means for feeding said paper strips to said crimping rolls, means 85 for guiding a crimped strip from said rolls to said table, a guard plate normally raised over the table where a crimped strip is deposited, means for swinging said plate downwardly into parallelism with and a distance above said table to form a passageway therewith, an abutment at the end of said passageway, guide slots at the bases of said side walls, a presser bar journaled at its ends in said guide slots, means for reciprocating 90 said presser bar, engagement of said presser bar in said passageway causing it to receive and to shift said crimped strip against said abutment, grooves in said table and plate, and guide tongues on said bar engaging 95 with said grooves.

11. In a crimping and folding machine, the combination of a supporting table, crimping rolls over said table for crimping paper strips and delivering them to said 100 table, a guard plate on said table over the section thereof receiving the crimped strip, a spring hinge for said plate tending to force it downwardly into parallelism with said table over the strip received thereon, an 110 abutment at the hinged end of said plate, a presser bar shiftable on said table into and out of the passageway between said table and plate, said bar when entering said passageway shifting said crimped strips toward 115 and against the abutment and pressing it to cause compact folding together thereof, and means for ejecting a finished strip from said table.

12. In a crimping and folding machine, 120 the combination of crimping rolls for crimping a paper strip, means for transversely compressing and compactly folding together said strips after the crimping operation, and means for confining said strip under vertical 125 pressure during the folding operation.

13. In a machine for crimping and folding strips, the combination of crimping rolls for crimping the strips, upper and lower 130 guide walls between which a crimped strip

is received, an abutment wall at the ends of said guide walls, a presser bar and means for shifting it between said guide walls to cause compression thereby of the crimped strip 5 against said abutment, one of said guide walls being yieldable to thereby permit increase of thickness of strips during the compact folding thereof.

14. In a crimping and folding machine, 10 the combination of a supporting table, crimping rolls over said table for receiving and crimping said paper strips, a guard plate on said table, spring levers tending to swing said guard plate into parallelism with 15 said table, cam mechanism for holding said guard plate in raised position, means for guiding a crimped strip from said rolls to said table below said plate, said cam mechanism and spring levers coöperating to swing 20 said plate into parallelism with the table above said strip, an abutment, a presser bar guided on said table, and cam mechanism for shifting said presser bar along said table below said plate to engage with and 25 to compress and compactly fold said strip against said abutment.

15. In a crimping and folding machine, the combination of a supporting table, crimping rolls journaled above said table, means for feeding a paper strip to said crimping rolls, means for guiding a crimped strip from said rolls to said table, a guard plate hinged on said table and normally held raised above the table to permit application thereon of a crimped strip, means for 35 swinging said plate downwardly into parallelism with the table above said strip, a presser bar, said table and said plate having guide grooves, guide tongues on said presser bar engaging in said grooves to guide said bar, means for reciprocating said bar toward and away from said strip, inward travel of 40 said bar causing engagement thereof with said strip and compression thereof to compact form, ejector arms slidably in said 45 grooves, and means for shifting said bars to discharge the compressed strip from said table.

In witness whereof I hereunto subscribe my name this 1st day of March, A. D., 1920. 50

JOSEPH W. HOODWIN.
